[57] CLAIM

The ornamental design for a game control console, as shown and described.

DESCRIPTION

FIG. 1 is a perspective view of a game control console employing our new design.

FIG. 2 is a top plan view of the game control console shown in FIG. 1.

FIG. 3 is a front elevational view of the game control console shown in FIG. 1.

FIG. 4 is a bottom plan view of the game control console shown in FIG. 1.

FIG. 5 is a rear elevational view of the game control console shown in FIG. 1.

FIG. 6 is a right side elevational view of the game control console shown in FIG. 1.

The left side elevation of the game control console is a mirror image of the right side.
